UNITED STATES PATENT OFFICE.

HARRY R. MASON, OF OAK PARK, ILLINOIS.

FLUID-PRESSURE SIGNAL-VALVE.

SPECIFICATION forming part of Letters Patent No. 534,401, dated February 19, 1895.

Application filed December 7, 1894. Serial No. 531,090. (No model.)

To all whom it may concern:

Be it known that I, HARRY R. MASON, a citizen of the United States, residing at Oak Park, in the county of Cook and State of Illinois, have invented a new and useful Improvement in Fluid-Pressure Signal-Valves, 5 of which the following is a specification.

My invention relates to improvements in a certain signal valve, which constitutes one of 10 the principal features of fluid-pressure signaling systems for railway-trains, and is usually located upon the engine cab to be actuated, by signaling impulses in the signaling-pipe, to operate the signal.

15 My present improvement relates to a signal valve of the "non-interference" type, the name being given to valves of this particular class because they are constructed to prevent such interference, from rebounding signaling 20 impulses as would cause undue repetition of the signal.

In Letters Patent of the United States No. 512,889, granted to me January 16, 1894, I show, describe and claim a "non-interference" signal-valve, the non-interference principle being carried out with mechanism operating automatically, after the signal has been sounded once under the action of the direct impulse, to shut off the signal temporarily, 25 whereby fluctuations of pressure in the signaling-pipe, following upon the direct impulse, have no effect upon the signal.

30 My present object is to provide a signal-valve with improved mechanism, which shall operate to prevent interference from rebounding impulses, in a train of any length and without the necessity of adjustment according to the length of the train, by causing such lowering of the signal-reservoir pressure under the direct signaling impulse, that it will not act to sound the signal under the rebound. 35 As I prefer to provide my present improvements they are so constructed that under mild direct impulses, as where the train is very long, the signal-valve piston or abutment will be caused to rise and fall naturally, without hindrance, under variations of pressure between the signaling-pipe and signaling-reservoir; and that under more severe impulses 40 the return of the signal valve piston will be retarded, the degree of retardation being governed by the severity of the direct impulse.

By retarding the return of the signal-valve piston the degree of pressure vented from the signaling-reservoir is increased and the signaling-reservoir pressure thus lowered to a degree which will prevent its lifting the signal-valve piston against the reduced counter-pressure upon the piston occasioned by rebounding impulses following the direct impulse. 55

60 My object is, further, to provide mechanism for carrying out my invention, of a simple, durable and economical construction.

The drawing shows a vertical central section of a valve-device involving my improvements. 65

A is the valve which is formed, preferably, in two sections A' A² fitting together with an intervening gasket t. The lower section A² 70 is formed with a chamber s which, at its upper end, communicates through a cored passage r with a pipe B leading to the signaling or train-pipe, not shown. On the shell at r' and communicating with the passage r is the usual train or signal pipe pressure gage, not shown. At the base and center of the chamber s is a port q surrounded by a valve-seat q', and leading to a cored passage q² which extends to a signal C, which may be a whistle, 75 as shown. Extending partway about the valve-seat q' is a port p leading to a passage p' which communicates with the signaling-reservoir, not shown. In the upper part of 80 the chamber s is an annular bushing s', and working in said bushing is a movable abutment, preferably in the form of a piston, n, upon a stem n' sliding through a sleeve or bushing supported by the part s² in the chamber s. At its lower end the stem n' is formed 85 into a valve n² to fit the valve-seat q' and close the port q. The piston n is out of immediate contact at its circumference with the bushing s' to afford an annular passage in 90 the chamber s between opposite sides of the piston. This annular space is the only passage between the train-pipe and signaling-reservoir, and, for the purpose of illustration, 95 is exaggerated in the drawing.

In the upper section A', and in open communication with the chamber s, is a chamber l of smaller diameter than the chamber s and provided with an annular bushing l'. In the chamber l is a piston k having a stem k' which 100

slides in a cored guide l^2 in the shell. The piston k fits the bushing l' loosely to permit air to pass between the chambers s l around the circumferential face of the piston. Projecting downward from the piston k is a stem k^2 provided in its end with a socket k^3 which receives and slides over a lug n^3 on the piston n . Extending through the lug n^3 is a transverse opening n^4 enlarged in the vertical direction; and fastened in the sleeve or stem k^2 and passing through the slot n^4 is a cotter k^4 . Fastened against the under face of the shell-section A' in the chamber s is a stop-plate k^5 held in place by a screw k^6 . The stop-plate k^5 projects across the path of the piston k and limits the movement of the latter in the downward direction. When the piston n is down, to seat with the valve n^2 upon the valve-seat q' , and the piston k rests upon the stop-plate k^5 the cotter k^4 extends through the upper part of the opening n^4 leaving an appreciable space between the lower wall of the opening and the cotter. When the piston n rises, as hereinafter explained, it moves a distance limited by said space before the lower wall of its opening n^4 strikes the stop or cotter k^4 , and in its further rise the piston would have to raise the piston k .

In the upper part of the shell-section A' is a chamber i closed at the top by a screw-cap i' . Extending from the passenger to the chamber i is a cored passage i^2 , and extending from the chamber l to the chamber i is a vent-passage i^3 . Around the passage i^3 in the chamber i is a valve-seat i^4 upon which fits a check-valve i^5 . The check-valve i^5 is of predetermined weight and effectually closes the passage i^3 . On the screw i' is a stop i^6 which limits the rise of the valve i^5 from the seat i^4 .

In operation, air under pressure from the signaling-pipe B enters the cored passage r and fills the chambers s i . From the chamber s the pressure passes, somewhat slowly, around the piston n and through the passage p p' to the signaling-reservoir; and pressure also passes from the chamber s around the piston k to the chamber l . The chambers s l i and the signaling-reservoir are thus charged with air under a pressure equal to that of the signaling-pipe. The weight of the piston n and the suction effect against the valve n^2 at the port q , maintains the said piston and valve seated and the port q closed. The piston k rests normally upon the stop k^5 , and the valve i^5 is maintained normally closed by gravity.

All the conductor's signaling valves which I prefer to provide for my improved signaling-system are constructed with a view to venting with each operation a certain predetermined volume or degree of pressure with each operation, so that each time they are actuated the generated impulse will be the same. All my conductor's signaling-valves are constructed alike, so that in a train of any number of cars a signaling impulse will be initially of the same negative force no matter upon

what car it is generated. A signaling impulse generated at a conductor's signaling-valve in a long train is necessarily weaker, when it reaches the signaling-valve, than it would be in a short train. In Letters Patent hitherto granted to me I have explained, and it is now well-known in the art, that a signaling impulse when it travels to the end of the signaling-pipe rebounds, the force of the rebound being proportional to the force of the direct impulse. As also explained in patents hitherto granted to me there is always danger when the signal has been actuated by a direct impulse that it will be actuated a second time by the rebounding impulse if no means are provided to prevent it. The means I provide in the present construction produce such venting or lowering of the signal reservoir pressure under the direct impulse that the reservoir pressure will be approximately as low as, or lower than, the pressure above the piston n when the rebounding impulse is felt in the chamber s above the said piston. To accomplish this the piston n , as I prefer to provide it, is made sufficiently sensitive to rise and cause operation of the signal under an impulse generated at a conductor's signaling valve in a train of, say, eighteen cars,—eighteen passenger cars being usually the limit in number allowed for any one train by railroads. Under a signaling impulse generated in a train of eighteen cars the piston n will rise to the stop k^4 , and when by venting through the port q the signaling reservoir pressure falls approximately to that in the train-pipe, the piston will drop and close the port q . The rebounding impulse will reach the piston, before there has been time for any material replenishment of the reservoirs, and a rebounding impulse will not lower the pressure above the piston n sufficiently to cause it to be moved from its seat by the reservoir pressure.

The piston k may be said to perform two functions, because in the first place it presents a yielding counter-force to that which raises the piston n , and then when it has been moved from normal position by the force of the piston n , in the rise of the latter, it presents a yielding counter-force to that which lowers the piston n . Thus an impulse of greater force than that necessary to lift the piston n alone, causes the latter to lift the piston k , and expel air from the chamber l to the chamber i against the resistance of the weighted valve i^5 . The greater the signaling impulse the greater the rise of the piston k , and the rise of the piston is therefore proportional to the strength of the impulse. In order that the piston k may return to normal position air must pass around the said piston from the chamber s to the chamber l . The greater the rise of the pistons, therefore, the slower their return to normal position, and the longer the port q will remain open to vent pressure from the signaling reservoir.

In practice I prefer to so construct the apparatus that the piston n will be lifted only to the

stop k^4 under a signaling impulse generated in a train of from fourteen to eighteen cars. In a shorter train of cars a signaling impulse will reduce the pressure above the piston n so far below that in the signaling reservoir that the piston n will be raised to the stop k^4 and then raise the piston k in the chamber l , the force causing the pressure in the chamber l to raise the weighted valve i^5 and thus vent more or less of the pressure from the chamber l . When the impulse has passed, and pressure rises in the train-pipe and above the piston n , the lowering of the latter is retarded by the piston k , which can move, as stated, no faster than the pressure entering the chamber l around the piston k will permit. Pressure will vent from the signaling-reservoir to the signal until the valve n^2 is closed and the degree of venting is commensurate with the rapidity of return of the pistons n k , or, primarily, with the force of the direct signaling impulse. Under an impulse generated in a train of from ten to thirteen cars the piston k will rise but slightly and retard the return of the piston n but slightly, and so on as the train is shortened the degree of rise of the pistons will be in proportion to the force of the direct impulse, which later will be, approximately, in inverse proportion to the number of cars in the train. In a train of from one to four cars the piston k will be lifted to the top of the chamber l and its return made proportionately slow. In every instance the pistons will be raised and the port q caused to remain open a length of time sufficient to vent enough pressure from the signaling-reservoir to prevent the rebounding impulse from causing a second rise of the piston n . It is of course desirable to economize air as much as possible and for this reason the parts should be adjusted with sufficient nicety to permit just enough and no more pressure to be vented from the signaling-reservoir than is necessary with each operation. Following the action of each direct impulse, pressure is equalized with desired quickness between opposite sides of the piston n by the passage around it of pressure from the train-pipe to the signaling-reservoir.

In its broadest sense the gist of my invention lies in providing mechanism which will operate automatically to retard the closing or return of the valve, at the outlet port to the signal, whereby under all conditions sufficient pressure will be withdrawn from the signaling-reservoir to prevent the piston from being raised by the rebounding impulse. My invention further consists, in providing retarding mechanism for the said valve which will be governed in its action by the force of the direct or original impulse, so that under a comparatively strong impulse, which would be followed by a correspondingly strong rebound, the signaling-reservoir will be vented to a greater degree than under a comparatively weak impulse.

In carrying out my invention I employ the

construction shown in the drawing, and I prefer it to any other construction, at present, because it is the best I have tried, and it operates well. My invention, in spirit, however, may be carried out with mechanism variously modified, and I do not wish it to be limited in its broad sense to any particular construction of return-retarding mechanism for the valve.

What I claim as new, and desire to secure by Letters Patent, is—

1. In a fluid-pressure signaling-system, the combination with a signal-valve device provided with valve-mechanism interposed between a signaling-pipe and a signaling-reservoir, and subject on its opposite sides to pressure therefrom, respectively, and normally closing an outlet from said reservoir to the signal, and movable from normal position to open said outlet under pressure from the said reservoir when the train-pipe pressure falls under a signaling impulse, of return retarding mechanism for the said valve-mechanism supplementing the action of the reservoir pressure to afford yielding resistance to the return of the valve-mechanism to normal position under the rise of pressure in the signaling-pipe following said impulse, substantially as and for the purpose set forth.

2. In a fluid-pressure signaling-system, the combination with a signal-valve device provided with valve-mechanism interposed between a signaling-pipe and a signaling-reservoir, and subject on its opposite sides to pressure therefrom, respectively, and normally closing an outlet from said reservoir to the signal, and movable from normal position to open said outlet under pressure from the said reservoir when the train-pipe pressure falls under a signaling impulse, of return retarding mechanism for the said valve-mechanism governed in the extent of its retarding action by the force of the signaling impulse and supplementing the action of the reservoir pressure to afford yielding resistance to the return of the valve-mechanism to normal position under the rise of pressure in the signaling-pipe following said impulse, substantially as and for the purpose set forth.

3. In a fluid-pressure signaling-system, the combination with a signal-valve device provided with valve-mechanism interposed between a signaling-pipe and a signaling-reservoir, and subject on its opposite sides to pressure therefrom respectively, and normally closing an outlet from said reservoir to the signal, and movable from normal position to open said outlet under pressure from the said reservoir when the train-pipe pressure falls under a signaling impulse, of return retarding mechanism for the said valve-mechanism in the path of the said valve-mechanism to be engaged and moved thereby after the said valve mechanism has been moved a predetermined distance from its normal position, and supplementing the action of the reservoir pressure to afford yielding resistance to the

return of the valve-mechanism to normal position under the rise of pressure in the signaling-pipe following said impulse, substantially as and for the purpose set forth.

- 5 4. In a fluid-pressure signaling-system, the combination with the valve-device provided with a piston interposed between a signaling-pipe and a signaling-reservoir and subject on its opposite sides to pressure therefrom respectively, and normally closing an outlet from the said reservoir to the signal, and movable from normal position to rise and open said outlet under pressure from the said reservoir when train-pipe pressure falls under 15 a signaling impulse, of return-retarding mechanism at the said valve-device for the said piston, comprising a chamber having a vent opening, a movable abutment in said chamber at one side exposed to signaling pipe pressure and connected with the said piston, and a small feed passage between opposite sides of said abutment, the piston operating, when raised, to engage and move said abutment to 20 expel air from said chamber through said vent opening and a check-valve at said vent opening, whereby the speed of the return of the piston and abutment to normal position is regulated by the speed of entrance of air to said chamber through said feed passage, 25 substantially as and for the purpose set forth.
5. In a fluid-pressure signaling-system, the combination with the valve-device provided with a piston interposed between a signaling-pipe and a signaling-reservoir and subject on 30 its opposite sides to pressure therefrom respectively, and normally closing an outlet from the said reservoir to the signal, and movable from normal position to rise and open said outlet under pressure from the said reservoir when train-pipe pressure falls under 35 a signaling impulse, of return-retarding mechanism at the said valve-device for the said piston, comprising a chamber, a comparatively large vent passage from the chamber to the signaling-pipe, a check-valve v^5 at said vent-passage, a comparatively small feed 40 passage from the signaling-pipe to the said chamber, and a movable abutment in said chamber at one side exposed to signaling-pipe pressure and connected with the said piston, the piston being movable for a predetermined distance independent of said abutment, and operating when raised beyond said predetermined distance, to engage and move 45 said abutment to expel air from said chamber through said vent opening to the signaling-pipe against the resistance of the valve v^5 , and the return of the abutment and piston to normal position being regulated by the speed of entrance of air to said chamber through said feed passage, substantially as and for the purpose set forth.

chamber at one side exposed to signaling-pipe pressure and connected with the said piston, the piston operating, when raised, to engage and move said abutment to expel air from said chamber through said vent opening to the signaling-pipe against the resistance of the valve v^5 , and the return of the abutment and piston to normal position being regulated by the speed of entrance of air to said chamber through said feed passage, substantially as and for the purpose set forth.

6. In a fluid-pressure signaling-system, the combination with the valve-device provided with a piston interposed between a signaling-pipe and a signaling-reservoir and subject on its opposite sides to pressure therefrom respectively, and normally closing an outlet from the said reservoir to the signal, and movable from normal position to rise and open said outlet under pressure from the said reservoir when train-pipe pressure falls under a signaling impulse, of return-retarding mechanism at the said valve-device for the said piston, comprising a chamber, a comparatively large vent passage from the chamber to the signaling-pipe, a check-valve v^5 at said vent-passage, a comparatively small feed 75 passage from the signaling-pipe to the said chamber, and a movable abutment in said chamber at one side exposed to signaling-pipe pressure and connected with the said piston, the piston being movable for a predetermined distance independent of said abutment, and operating when raised beyond said predetermined distance, to engage and move 80 said abutment to expel air from said chamber through said vent opening to the signaling-pipe against the resistance of the valve v^5 , and the return of the abutment and piston to normal position being regulated by the speed of entrance of air to said chamber through said feed passage, substantially as and for the purpose set forth.
